UNITED STATES PATENT OFFICE

EDWIN F. BRITTON, JR., OF MAPLEWOOD, NEW JERSEY, ASSIGNOR TO MONROE CALCULATING MACHINE COMPANY, OF ORANGE, NEW JERSEY, A CORPORATION OF DELAWARE

CALCULATING MACHINE

Application filed May 29, 1930. Serial No. 457,004.

This invention relates to calculating machines and particularly to machines adapted for calculations in British currency, and the principal object is to provide a selecting mechanism whereby calculations may be optionally performed by either fractional, decimal equivalent, or straight decimal methods at the will of the operator.

Another object of the invention is to provide a shiftable selecting mechanism wherein the same keys are used for both decimal and decimal equivalent calculations.

Another object is to provide a means to release the depressed keys before the selecting mechanism is moved from decimal position to decimal equivalent position or vice versa.

Another object is to provide detent means for holding the selecting mechanism when shifted to the desired position.

20 A further object of the invention is to provide a calculating machine, adapted for British currency calculations, with means to prevent the product wheels from being accidentally shifted from straight decimal or decimal equivalent to fractional position, or out of fractional position, once the machine has been set.

Other objects will appear from the following description and will be pointed out in the 30 appended claims. I attain all of these objects by the means shown in the accompanying drawings, in which:

Fig. 1 is a somewhat diagrammatic top plan view of a machine embodying the invention.

Fig. 2 is a right-hand side elevation with parts broken away for clearness.

Fig. 3 is a vertical sectional view taken substantially on line 3—3 of Fig. 1.

Fig. 4 is a vertical sectional view taken substantially on line 4—4 of Fig. 1.

Fig. 5 is a vertical sectional view taken substantially on line 5—5 of Fig. 1.

Fig. 6 is a detail perspective view of the pence numeral wheel.

Fig. 7 is a detail perspective view of the units of the shillings numeral wheel.

Fig. 8 is a detail perspective view of the tens of shillings numeral wheel.

Fig. 9 is a detail perspective view of a decimal numeral wheel.

Fig. 10 is a detail perspective view of the pence selector gears.

Fig. 11 is a detail perspective view of a portion of the key mechanism.

Fig. 12 is a fragmentary vertical sectional view taken substantially on line 12—12 of Fig. 5.

Fig. 13 is a detail perspective view of a portion of the key mechanism used in the decimal equivalent column.

Fig. 14 is a fragmentary vertical sectional view taken through the "0" key of the shiftable column of keys.

Fig. 15 is a fragmentary top plan view of certain selector bails and associated parts.

Fig. 16 is a fragmentary detail view of a part of the key mechanism.

Fig. 17 is a diagrammatic top plan view of the keyboard, indicating keys to be ignored when calculations in British currency by the decimal equivalent method are being effected.

Fig. 18 is a similar view indicating keys ignored when working in British Currency by fractions.

Fig. 19 is a similar view indicating the keys to be ignored when using the machine for straight decimal calculation.

Fig. 20 is a fragmentary top plan view of a machine embodying a modified form of the invention.

Fig. 21 is a fragmentary right-hand side elevation of the form shown in Fig. 19, the casing being broken away for clearness.

Fig. 22 is an enlarged fragmentary vertical sectional view taken just inside the right-hand side frame showing the modified form more clearly.

Fig. 23 is a fragmentary vertical section

taken through the bail shifting plate of the modified form.

Fig. 24 is a detail perspective of the modified form of means for shifting the bails in the second, third, fourth and fifth columns from the right.

Like characters of reference refer to like parts in all views.

Before describing the invention in detail, it may be helpful to mention that by way of illustrating the application of my invention, I have chosen to show the same as incorporated in a calculating machine of the well-known Monroe construction, although this is to be considered as merely illustrative, the invention being applicable to machines of various types.

The general construction and operation of the Monroe type of machine is set forth in the U. S. Patent No. 1,566,650 issued to George C. Chase, December 22, 1925, as modified by Patent No. 1,664,661 issued to George C. Chase entitled Full cycle positioning mechanism, and is well known in the art, having been incorporated in a great number of machines placed on the market and in wide general use.

It may be well at this point to indicate the intended meanings of certain phrases used in this specification. The term "fraction" or "fractional method" or kindred expressions as used herein refers not to vulgar fractions as might be supposed, but to dealing with monetary values not based on a decimal system. The term "decimal equivalent" means the conversion of values not based on a decimal system to corresponding decimal system values. Thus $10d. + 4d. = 1s. 2d.$ is considered as a "fractional" system addition; and by changing the problem into "decimal equivalents" we would have $\text{£}0.04167 + \text{£}0.01667 = \text{£}0.05834$.

Referring to the drawings in detail, 30 designates the casing and 31 the side frames 45 of the machine. A keyboard is shown at 32 and guides a plurality of manipulative key members as follows: fraction keys 33 used only in fractional calculations; digit-setting keys 34 and zero keys 35, a column of decimal 50 equivalent setting keys 36, and zero key 37, keyboard clearing key 38, repeat key 39, non-repeat key 40, add-operating key or plus bar 41, subtract-operating key or minus bar 42, division lever 43, and multiplying keys 45. 55 A driving motor is shown at 46, a hand-operating crank at 47 and a carriage at 48. The carriage 48 carries a plurality of accumulator dials as follows: a pence accumulator dial 49, a units of shillings accumulator dial 50, a tens of shillings accumulator dial 51, and a plurality of standard ten-point accumulator dials 52. A counter dial 53 registers only when the carriage is in the position shown in Fig. 1; and counters 54, being of 60 the nineteen point type, have no carrying

mechanism and each bears the nine significant digits running in reverse directions from a common zero, one set of significant digits being colored differently from the other. One or more sets of ten-point counters 70 might be used alternatively and if ten-point counters were used, no special dial 53 would be necessary, since with the ten point arrangement, a dial in this position would carry over to the successive left-hand dials. 75

The motor driving means is illustrated substantially the same as that disclosed in the Patent No. 1,566,650 issued to George C. Chase, motor 46 having connections with a planetary gear mechanism, the gear members of which normally rotate idly but may be selectively arrested by means of a reversing clutch lever (not shown in the drawings), whereby the third member of the differential connected with shaft 55, is driven forward 85 or reversely, respectively.

Motor operation is controlled by means of the add key 41, and the subtract key 42 as fully explained in Patent No. 1,566,650, hereinbefore referred to. 90

British currency calculations by fraction method

(Figs. 1, 2, 4, 6 to 12, 15 and 18.) To perform calculations in British currency by 95 the fractional method, the carriage 48 must be moved to the extreme left position as shown in Fig. 1, to bring the pence accumulator dial 49 in alignment with the column of pence or fraction keys 33. 100

The three right hand dials are adapted for fractional calculations in British currency and shown to be of a different color from the rest of the dials. The pence dial 49, Figures 1, 4 and 6 is provided with one 105 set of twelve numbers, from "0" to "11" inclusive and the gear 56 attached thereto has twelve teeth. This gear is provided with one carry tripping pin 57 clearly shown in Fig. 6. The units of shillings dial 50 is provided with one set of ten digits from "0" to "9" inclusive, and the attached gear 58 has ten teeth and one carry tripping pin 59, Fig. 7, the same as the accumulator dials 52 shown in Fig. 9, except in color. The tens 110 of shillings dial 51 (the third dial from the right), Figs. 1 and 8 is provided with five "1's" equally spaced on the face of the dial which leaves a blank space therebetween and the attached gear 60 has ten teeth and five 115 carry pins 61. The dials 52 to the left of these fraction dials are as shown in Fig. 9, the construction being that of the well known Monroe ten-point accumulator dials. The carry mechanism, as described in above-mentioned patents, will advance the next higher dial one step when a carry tripping pin 120 is turned to carry position. 125

As the pence numeral dial 49 travels from "11" to "0" the carry pin 57 operates the tens 130

carry mechanism, described in Patent No. 1,566,650, which advances the next dial 50, representing the units of shillings, one step upon each revolution of the pence dial. As the units of shillings dial 50 travels from "9" to "0" the carry pin 59 operates the tens carry mechanism to advance the tens of shilling dial 51 one step and one of the "1's" is brought into alignment with the sight opening. Upon the next revolution of the units of shillings dial and a carry into the tens of shillings dial, the tens of shillings dial 51 is turned to show a blank, and while turning from "1" to a blank, one of the carry tripping pins 61 operates the carry mechanism and advances the dial to the left, one step, which in this form of calculation would represent one pound sterling.

The keys in the diagrammatic top plan view of Fig. 18 show the ones to be depressed to enter pounds, shillings, and pence in to the accumulator dials which are aligned therewith as described. The keys crossed off in this figure are to be ignored while performing fractional calculations. The columns of keys to the left of the column of pence keys and the "1" key which represents tens of shillings in the third column are of a different color to enable the operator to select the units and tens of shillings more readily.

By referring to the diagrammatic top plan view Fig. 18 one can readily see and understand the keys to be used and the ones to be ignored while performing calculations by fractions. The pence keys 33 include the ten digit keys and a "10" and an "11" key, the last two of which act upon a set of selector bails 62 and 63, which in turn shift selector gears 64 and 65, respectively, to register the number represented by the key depressed, by turning an intermediate gear 66, which is in constant mesh with the gear 56 on the dial, the required number of steps. The bail 62 is provided with diverging lugs in sets of threes, while the bail 63 is provided with two sets of lugs each set extending at a different angle. The bail 62 may move one, two or three steps and the bail 63 may move either one or two steps, according to the selecting gear section the respective bail moves into operative position. The selecting gear 64 has three sections 67, 68 and 69 formed with one, two and three teeth respectively, and the gear is moved by the depression of the keys 1, 5 and 9, to align section 67 with gear 66, and it is moved by keys 2, 6 and 10 to align section 68 with gear 66, and by keys 3, 7 and 11 to align section 69 with gear 66, whereby one, two or three teeth will be brought into position to engage the intermediate gear 66 to advance or retract the dial 49. The selector gear 65 actuated by the selecting bail 63 comprises two sections 70 and

71, formed with four and eight teeth, respectively, section 70 being moved into alignment with the intermediate gear 66 by keys 4, 5, 6 and 7 and section 71 being moved into alignment with gear 66 by keys 8, 9, 10 and 11.

The selector gears 64 and 65 as shown in Fig. 10 are the only set of this kind, the remaining selector gears being the same as described in the Patent 1,399,652 granted to E. E. Phinney on December 6, 1921.

The intermediate gear 66 has fourteen teeth, the same as all of the other intermediate gears 72 to the left thereof.

To bring the manipulative key stems for the "10" and "11" keys of the right-hand column within the limits of the selector bails, I provide an arm 73 extending forwardly from the vertical portion 74 of the "10" key. This arm 73 is provided with a finger 75 at its forward end to extend into a notch 76 in the edge of a short stem 77 arranged forward of the stem of the "9" key. The "11" key is provided with two vertical elements 78 having horizontally bent portions at their lower ends, which are fixed to a key stem 79 for operating the latter, which is arranged in rear of the stem of the "9" key. The upper portion of the two elements 78 merge into horizontal plate 80 which is provided with a vertical bent portion 81, Fig. 11 extending through the keyboard frame and carrying the "11" key button.

Due to the spacing of the two stems 77 and 79 with relation to the stem of the "9" key, the "9", "10" and "11" keys are held in raised position by clips 82, attached to the key stems, and held up by springs 83 attached to a stationary pin 84 extending forward from a stationary cross frame 85 as shown in Figs. 3, 4 and 16.

When performing calculations by fractions it is necessary to keep the dial 49 in vertical alignment with the columns of pence keys 33 and to prevent accidental displacement of the carriage. I provide a carriage-positioning bridge 86 rigidly mounted on the keyboard 32, in such a position that a pin 87 projecting from the carriage will strike the left side of the bridge when the carriage is in proper position for fractional work. The height of the bridge is sufficient to prevent any movement of the carriage to the right by the turning of the well known carriage shifting knob 88. The length of the bridge is sufficient to hold the carriage in its ineffective raised position while being shifted two spaces, and such shifting must be done by direct manipulation of the carriage.

Amounts set up on the keyboard by the depression of the keys, and thereby set up on the selecting gears, are registered upon the accumulator dials by the turning of the

selector shaft 89 and the shaft 55 on which the tens carry members are mounted.

The shaft 55 may be driven from the motor 46 by being connected to the motor shaft 5 upon depression of the plus bar 41 or minus bar 42 as is well known in the art. A gear 90 is secured to the shaft 55 and meshes with a gear 91. The gear 91 meshes with a third gear 92 which may be optionally operated 10 by the hand crank. These three gears 90, 91 and 92 have a 1-to-1 ratio so that rotation of either gear 90 or gear 92 causes comitant rotation of gear 91. Secured to gear 91 is an elliptical gear 93 which meshes 15 with an elliptical gear 94 secured to the selector shaft 89, so that while the tens carry shaft 55 is traveling at a constant speed ratio, the selector shaft 89 is driven at a variable rate of speed.

British currency by the decimal equivalent method.

(Figs. 1, 5 and 11 to 16 inclusive.) To 25 set the machine to perform calculations by the decimal equivalent method, the carriage 48 must be moved two spaces to the right, to align the right hand one of the accumulator dials 52 with the second column of 30 keys from the right-hand side of the machine, and must be moved manually from the fraction position previously explained, as the carriage shifting knob 88 will not raise the front of the carriage high enough 35 to permit the pin 87 to clear the bridge 86. It will, of course, be understood that the carriage may be moved freely to all positions on the right-hand side of the bridge.

The three right hand columns of keys are 40 not used in performing calculations by the decimal equivalent method as clearly shown in the diagrammatic top plan view Fig. 17, although the selector bails of the second and third column from the right, are used to set 45 up the fourth and fifth places of the decimal equivalent. For this purpose I have provided the lower ends of the keys 36 in the fourth column from the right, with cross, or cam bars 95 rigidly attached thereto but 50 spaced therefrom so that the bars will, as clearly shown in Figs. 5 and 13, register with the recesses between the lugs on the selecting bails of the second, third, fourth and fifth columns from right, when the 55 machine is used for straight decimal calculations or fractional work. Therefore, preparatory to doing decimal equivalent work, this fourth column of keys must be moved toward the front of the machine to bring the 60 cam bars 95 over the extra lugs provided on the selecting bails operable by the bars, as shown in Figs. 5 and 15. To shift the fourth column I provide separate upper and lower 65 key guide plates 96 and 97, rigidly mounted 70 on end frames 98 and 99, and guided in

grooves 100 provided on the keyboard 32; the lower plate is held within the plane of the lower keyboard frame 101, by a plate 102 attached to and slidble with the lower plate 97. The outer edges of the plate 102 are turned down at right angles and provided with grooves for guiding the outer ends of the cam bars 95. This column of keys 36 and 37 slides a distance equal to the space between the centers of the lower end 75 of the key stem and the attached cam bar 95 and is operated by a manipulating handle 103 attached to and extending from the front end of the upper plate 96.

To prevent accidental shifting of this column of keys, I provide the stem of the zero key 37 with a forwardly extending pin 104 provided with reduced portions or notches 105 and 106 which engage a keeper 107, fixed to the edges of the stationary keyboard 32, as shown in Figs. 5, 12, and 13. When the machine is used as a decimal equivalent machine the notch 106 of the pin 104 is locked in the small portion of a key-hole slot formed in the keeper 107, and the column of keys cannot be returned to decimal or fractional position until the zero key 37 is depressed to disengage the pin 104 from the key-hole slot of the keeper 107, which causes any key in this particular column that stands in depressed position to be released. When the column of keys 36 and 37 has been moved to decimal or fractional position any numeral key depressed, will release the zero key, which is then raised by its spring, so that the notch 105 will engage the key-hole slot of the keeper 107 and lock the column in rear position.

The construction of the "10" and "11" key 36 in this column is identically the same as that of the corresponding keys for the pence fraction keys 33 except for the addition of a cam bar 95 to each of the stems 77 and 79, Fig. 5.

With the fourth column of keys from the right, moved to decimal equivalent position as shown in Fig. 17, the cross bars 95, on the lower ends of these keys will be in position to engage the added lugs on the second, third, fourth and fifth sets of selector bails from the right. The selector bails of these sets are indicated in Fig. 15 by the reference characters A and B, A indicating the "4-side" bails and B the "5-side" bails of these sets. The usual lugs have been reduced in width 110 and the added lugs are shown directly opposite the digits 1-9 between the bails and which indicate the values set up by the respective lugs. For example, should the "1" key 115 of the column of keys 36 be depressed, the significant digits of .00417 (decimal equivalent of one penny), will be set up by the first second and third sets of bails A and B. In Fig. 15, the decimal equivalent values of 1 to 11 pence are indicated by the small 120 numerals between the sets of selector bails 125 130

A and B. Large numerals to the left of all the bails indicate the usual nine digital values and similar numerals at the right, indicate the values necessary for registration in pence.

5 Inspection of Fig. 15 will therefore indicate that depression of the keys 36 will set up the following decimal equivalent values:

Key	Decimal equivalent
1	.00417
10 2	.00833
3	.01250
4	.01667
5	.02083
6	.02500
15 7	.02917
8	.03333
9	.03750
10	.04167
11	.04583

20 The added lugs on the several bails A and B are formed so as to be moved by the respective cam bars 95 the necessary distances to effect registration of the significant portions of the above table of equivalents, such 25 table having been based on

$$1d. = \text{£} \frac{1}{240}$$

30 When the cam bars 95 are in their operative position (i. e. when the keys 36-37 are forward), the usual cams on the lower ends of the key stems proper will be in alignment with recesses between the lugs so that when 35 the keys are depressed, the usual cams of keys 36 will have no effect upon the respective bails A and B.

The selector gears 108, and intermediate gears 72, from the second column from the right to the left of the machine are identical, 40 and operate as described in Patent 1,566,650, and the accumulator dials 52 are all of the usual ten point Monroe type, as illustrated in Fig. 9.

45 In setting up the decimal equivalents of shillings, it will be noted that multiples of five will be set (there being twenty shillings in a pound sterling). Referring to Fig. 17, it will be seen that shillings are to be set up 50 on the two rows of keys to the left of the movable keys 36, and small numerals are placed on certain of these keys, the "5" key of the right hand row having a small "1" inscribed on it and the keys of the left hand one 55 of these rows having small numerals "2" to "18" (even numbers only) inscribed thereon. When it is desired to set up an even number 60 of shillings, the key bearing this small number is depressed; but when it is desired to set up an odd number of shillings, the next lower even number key is set and also the key bearing the small "1" in the right hand one of these columns is set. It will, therefore, be noted that as the "5" key (bearing the small 65 "1") is the only key of this row ever set for

decimal equivalent work, the bail B associated with this row will be the only one set directly from this row of keys in decimal equivalent work, and as the decimal equivalent of pence never requires a setting of more than "4" by the bails of this row, the bail A of this set will be the only one ever operated in setting up decimal equivalents of pence, so that there will never be an interference or double control of either bail associated with this row.

Straight decimal calculations

(Figs. 1, 2, 3, 4 and 19.) When using the machine for straight decimal work, in addition, subtraction, multiplication and division, the pin 87 must be kept on the right hand side of the bridge 86, Fig. 1, and the keys in the fourth column from the right-hand side of the machine must be in decimal or rear position, Fig. 4, with the notch 105 of pin 104 locked in the key-hole slot in the keeper 107 to insure horizontal alignment of the shiftable column of keys 36 with the rest of the keys of the keyboard. The "10" and "11" keys of the shiftable column of keys 36 are ignored as well as the keys of the first column on right hand side of the machine as shown crossed off in Fig. 18. With parts in this position the machine may be used for straight decimal calculations in the usual well-known manner.

Modified form

(Figs. 20 to 24 inclusive.) A modified form of means for changing the machine from condition for fractional or straight decimal calculations to condition for decimal equivalent work and vice versa is shown in Figs. 20 to 24. In this form of the invention, certain sets of selector bails are moved with respect to their coacting columns of keys to effect such change. The keys 36 or those in the fourth column from the right-hand side of the machine remain stationary so that the cam ends of the key stems and the cross or cam bars 95 remain always in the same vertical plane, as shown in Fig. 22. The selector bails A and B of the second, third, fourth and fifth columns from the right-hand side 105 of the machine slide on their pivot pins 109 toward the rear of the machine in changing from fractional or straight decimal calculations to decimal equivalent calculations.

To shift the four sets of bails A and B, I provide a lever 110 pivoted to the right hand side frame 31 at 111, with its free or upper end projecting above the keyboard 32 through a slot 112 to provide a manipulating handle 113, Figs. 20, 21, 22 and 24. During the first part of travel of the lever 110 in either direction, a double cam 114 will force one end of a bell crank lever 115 downward by riding on a roller 116 on the free end of said lever 115. This lever 115 is the keyboard-clear 125

lever described and illustrated in the patent to Phinney Re. 16,207 and which lever when operated effects return to normal raised position of any previously depressed key.

5 The lever 110 is connected by a link 117 to a rock frame 118 pivoted on a rod 119 supported by the main frames. The rock frame 118 includes a cross plate 120 cut away so as to escape all of the bails except the bails A 10 and B. The high part of member 120 passes thru slots 121 which slots are wide enough to permit operation of the keyboard clear lever 115 prior to shifting of the bails A and B by the high part of member 120. By moving 15 finger piece 113 forward, the bails A and B are adjusted so that the usual cams of the key stems will cooperate with the usual lugs of bails A and B and ordinary decimal calculations may be performed. By moving 20 finger piece 113 rearward, the bails A and B are adjusted so that the decimal equivalent cross or cam bars 95 become effective and decimal equivalent calculations may be performed.

25 While I have described what I consider to be the most desirable embodiments of my invention for the purpose set forth, it is obvious that changes in form could be made without departing from the spirit of my invention, and I, therefore, do not limit myself to the exact details herein shown and described, or to anything less than the whole of my invention as hereinafter particularly pointed out in the appended claims.

35 I claim:

1. In a calculating machine, the combination with accumulators and actuating devices therefor, of selecting bails including two sets of value lugs and operable to control certain 40 of said actuating devices, a plurality of keys, a pair of operating elements operable by each of said keys and operatively associated with said lugs, and means for shifting said keys and elements as a unit to position to coact 45 with either of said sets of lugs at the will of the operator.

2. In a calculating machine, the combination with accumulators and actuating devices therefor, of selecting bails including 50 two sets of value lugs and operable to control certain of said actuating devices, a plurality of keys, a pair of operating elements operable by each of said keys and operatively associated with said lugs, and means for 55 shifting said lugs and elements with relation to each other for bringing said keys into operative relation to either of said sets of lugs at the will of the operator.

3. In a calculating machine, the combination with accumulators and actuating devices 60 therefor, of a plurality of rows of settable digit keys, a plurality of controlling devices, each controlling device being operatively associated with a respective actuating device 65 for controlling the actuating of said accum-

ulators and normally controllable by the keys of a respective row of digit keys, means for shifting one of said rows of keys from normal position so as to bring the same into effective relationship with a plurality of said 70 controlling devices, and means operable upon setting of a key to lock said row of keys against manual displacement from either position to which it is moved.

4. In a calculating machine, the combination with accumulators and actuating devices therefor, of a plurality of rows of keys each comprising settable digit keys and restoring keys, a plurality of controlling devices, each controlling device being operatively associated with a respective actuating device for controlling the actuating of said accumulators and normally controllable by the digit keys of a respective row, means for shifting one of said rows of keys from normal position so as to bring the same into effective relationship with a plurality of said controlling devices, and means cooperating with the restoring key of a shiftable row and operable upon setting of a key to lock said 80 row of keys against manual displacement from either position to which it is moved.

5. In a calculating machine the combination with registering means and a plurality of actuators therefor, of an element for controlling a single one of said actuators to effect registering of a certain value, an element for controlling a plurality of said actuators simultaneously as to the values registered thereby, a single key for operating both 90 of said elements and means for rendering either of said elements effective at the will of the operator.

Signed at Orange, in the county of Essex and State of New Jersey this 26th day of 103 May A. D. 1930.

EDWIN F. BRITTON, JR.
